(57) CLAIM

The ornamental design for a floor lamp speaker, as shown and described.

DESCRIPTION

FIG. 1 is front, right side, top perspective view of a floor lamp speaker showing my new design;

FIG. 2 is a rear, right side, bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is a bottom view thereof.

The broken lines in the drawings illustrate portions of the floor lamp speaker that form no part of the claimed design.
